UNITED STATES PATENT OFFICE.

LENOX SIMPSON, OF PITTSBURG, PENNSYLVANIA.

BRICK-KILN.

SPECIFICATION forming part of Letters Patent No. 349,756, dated September 28, 1886.

Application filed April 9, 1886. Serial No. 198,379. (No model.)

To all whom it may concern:

Be it known that I, LENOX SIMPSON, a citizen of the United States, residing at Pittsburg, in the county of Allegheny and State of Pennsylvania, have invented certain new and useful Improvements in Brick-Kilns, of which the following is a full, clear, and exact description.

In my application for Letters Patent for improvement in kilns, filed January 27, 1886, Serial No. 189,980, I described a kiln provided with a combustion-chamber situated above the heating or burning chamber, and so separated from the latter as to prevent the flame and products of combustion from coming in direct contact with the brick or other articles burned. In said form of kiln more than half the time required to complete the burn is occupied in driving off the moisture contained in the green brick. Those brick lying near the bottom of the kiln are slow to feel the effects of the heat, and consequently a considerably greater space of time is occupied in burning than I deem necessary.

The object of this invention is to facilitate the burning of the brick by applying the heat at the bottom, (as well as the top,) while at the same time the flames and products of combustion are prevented from coming in contact with the brick.

The invention consists in the means herein-after described for attaining said object.

In the drawings, Figure 1 represents a vertical longitudinal section of the kiln; Fig. 2, a vertical transverse section of same, and Fig. 3 a horizontal section.

Similar letters of reference indicate corresponding parts.

A is the kiln, provided with an arched top, *a*, forming a combustion-chamber, within which are consumed the gases and waste products from the fires.

B' are two bridge-walls situated a short distance from each end of the kiln, and extending vertically upward almost or quite to the spring of the arch.

b are zigzag air-passages connecting at the bottom with the outer air, and having vents at the tops of the bridge-walls.

C and D are fire-places situated at the opposite ends of the kilns below the level of the kiln-floor. The fire-places C connect with flues

c, which lie beneath the kiln-floor and open into the space between the bridge-wall B' and the end of the kiln. The fire-places D connect with flues *d*, (similar to flues *c*,) which open into the space between the bridge-wall B and the adjacent end wall of the kiln. The flues *c* and *d* alternate, the object being to produce, as near as possible, the same heat throughout the whole extent of the kiln-floor.

It will be seen that by the foregoing construction of kiln the fire encircles the brick without passing through them at any point. The brick are consequently unaffected by the sulphur and other impurities contained in the fuel, and at the same time there is a complete consumption of fuel and increased economy in the use of the latter; also, by this arrangement the brick are dried off and burned evenly in a short time.

e is the stack, connecting by means of throat *e* with the interior of the combustion-chamber, and *e'* is a damper in the stack-flue, by means of which the draft is regulated.

The operation is as follows: The kiln is filled as high as the top of the bridge-walls with brick arranged in the ordinary manner. Upon the top of the brick I prefer to place a layer of fire-brick or tile, to protect the green brick from the direct action of the flame. The fires are then lighted and the brick slowly dried off. When this has been thoroughly done, the heat is gradually increased until the brick have reached a proper temperature, when the fires are drawn and the dampers, fire-places, and air-flues closed. The brick are then allowed to slowly cool. While the brick are being dried off, the air flues remain closed; but when the heat is raised the flues are opened sufficiently wide to cause complete combustion of the gases, &c.

I am aware that fire-flues have been used at the bottom and sides of brick-kilns; but they have been perforated to let the products of combustion circulate through the bricks, while it is my especial object to prevent this, for reasons before stated.

Having thus described my invention, what I claim as new, and desire to protect by Letters Patent, is—

1. A brick-kiln provided with imperforate flues leading from the fire-places through the floor of the kiln and behind imperforate bridge-

walls at the end of the kiln, whereby the products of combustion cannot pass through the bricks.

2. The combination, in a brick-kiln, with the 5 brick-chamber and a superposed combustion-chamber, of an intermediate layer of fire-brick or tile, as and for the purpose specified.

3. The kiln A, provided with arched com-

bustion-chamber, fire-places C D, bridge-walls B B', provided with zigzag air-passages, and 10 stack E, having damper e', as and for the purposes described.

LENOX SIMPSON.
